STORAGE AND DISPENSING RECEPTACLE FOR ROLLED PAPER

Michael Danko, Millfield, Ohio, assignor of one-half to J. E. Wade, Millfield, Ohio

Application May 2, 1956, Serial No. 582,254

3 Claims. (Cl. 242—55.3)

This invention relates to an improved storage and dispensing receptacle for rolled paper, such as conventional toilet tissue rolls, the general object thereof being to provide a wall-mounted receptacle having an internal chamber proportioned to receive a plurality of such rolls in vertical order, the receptacle being provided at one side thereof with a hinged movable door normally closing the chamber, and wherein the receptacle at one end thereof carries an exteriorly disposed, roll-supporting arbor which is mounted at one end on a stationary wall of the casing and is supported at its opposite end by means carried by the door when the latter occupies a closed position.

Another object is to provide a receptacle so formed with means carried by the door to retain a paper roll positioned on the arbor against longitudinal displacement, and when the door is opened to admit of convenient placement of a roll in an operative position on the arbor.

A further object is to provide arbor-supporting means on the receptacle door in the form of a stud which, when the door is closed, is positioned in an axial socket formed in the door-engaging end of the arbor for the support of the latter, and wherein yieldable holding means are provided in the arbor socket for engaging the stud in order to positively but releasably retain the door in its position of closure.

With these and other ends in view which will readily appear as the nature of the invention is better understood, the same consists in the improved construction and novel arrangement and combination of parts which will be hereinafter fully described and particularly pointed out in the appended claims.

In the accompanying drawings there has been illustrated a simple and preferred form of the invention, it being understood, however, that no limitation is necessarily made to the precise structural details therein exhibited, but that changes, alterations, and modifications within the scope of the claims may be resorted to when desired.

In said drawings:

Fig. 1 is a perspective view of my improved storage and dispensing receptacle for paper rolls;

Fig. 2 is a vertical sectional view taken through the same;

Fig. 3 is a horizontal sectional view taken on the line 3—3 of Fig. 2.

Fig. 4 is a detail vertical sectional view on an enlarged scale disclosing the door-carried supporting means for the receiving end of the roll-supporting arbor; and

Fig. 5 is a detail view disclosing the receptacle door when equipped with a spring hinge.

Corresponding parts in the several figures are denoted by like characters of reference.

Referring more particularly to the drawings, my improved paper roll storage and dispensing receptacle or cabinet is formed to embody a vertically elongated casing composed of rigidly united front, back, side, top, and

2

bottom walls 10, 11, 12, 13, and 14, respectively. One side of the casing is open, and a door 15, hinged, as at 16, to the outer edge of the rear wall 10, is employed to close said open side. The casing when so formed provides an internal chamber, accessible by the opening of the door, for the reception of one or more (preferably two) inactively positioned rolls R of toilet paper or the like.

To support such a roll in an active accessible position 10 for ready use, the side wall 12 of the casing is extended at 17 so that it projects in this instance vertically below the horizontal bottom wall 14. This wall extension is apertured to receive a headed fastening screw 18, the threaded shank of said screw being received in an internally threaded bore formed axially in one end of a horizontally extending arbor 19 on which is replaceably mounted an actively positioned roll R, the arbor being thus stationarily supported by the casing.

The opposite or loading end of the arbor is formed 20 axially thereof with an open, flared-end socket 20. The lower extension portion 21 of the door 15 projects below the bottom of the casing and possesses the configuration of the side wall extension 17. This lower portion 21 of the door carries a fixed stud 22 which is of such length 25 and diameter as to be received within the arbor socket 20 in effecting the support of the loading end of the arbor when the door occupies its position of closure.

In this instance the stud is formed with an annular groove 23 which, when the door is fully closed, is disposed 30 for engagement with a spring-pressed ball element 24 which is seated in a pocket provided therefor in the arbor, a portion of the ball element projecting into the stud groove 23 when in registry therewith. By such means the door is positively but releasably maintained 35 in its position of closure, in which the stud 22 thereon supports the roll-loading end of the arbor, with the door extension 21 guiding an active roll positioned on the arbor and precluding longitudinal displacement thereof, the mere opening of the door rendering the operation of 40 loading or unloading rolls on the arbor simple and easy to perform.

In Fig. 5 a spring hinge 16a is provided for the mounting 45 of the door 15. Such a hinge normally maintains the door in its position of closure and eliminates the need for the spring-pressed ball element 24 in the arbor.

In this instance the rear wall of the cabinet or receptacle is provided with key hole-shaped slots 25 for the reception of the shanks of headed fastening elements projecting from an associated building or other wall to 50 which the receptacle is applied and supported. The receptacle possesses the advantage of admitting of one hand operation in opening and closing the door for roll-manipulating and positioning purposes. Its construction is simple, sturdy, and economical, and the casing 55 presents an inviting and attractive appearance in keeping with modern bathroom fixtures.

Having thus described my invention, what I claim as new and patentable is:

1. A combined storage cabinet and rolled paper dispenser comprising a generally vertically arranged casing structure including back, front, top and bottom walls, and a closed side wall, said casing being open at the side thereof opposite said closed side wall and defining an internal storage compartment for the reception of rolled paper, the closed side wall of said casing structure being extended vertically below the bottom wall thereof; a roll-receiving arbor secured at one end thereof to the vertically extended portion of said side wall and projecting generally horizontally below the bottom wall of 60 said casing structure, said arbor terminating at the opposite end thereof in a free end portion over which a

- 70

roll of paper may be freely passed; a door closure hingedly connected to the back wall of said casing structure and formed with a main body portion and a downward, vertical extension, said door closure being arranged to swing relative to said casing structure between a first position, wherein the main body portion of said door closure closes the open side of said casing structure and the downward extension obstructs the free end portion of said arbor, and a second position permitting free access both to the storage compartment of said casing structure and to the free end portion of said arbor; and means on the downward vertical extension of said door closure engageable with the free end portion of said arbor, when said door closure occupies said first-named position, for supporting the free end portion of said arbor in connection with 15 said door closure.

2. A combined storage cabinet and rolled paper dispenser as defined by claim 1, wherein the free end portion of said arbor is formed with an axially arranged

socket, and said last-named means comprises a horizontal stud arranged to enter the socket of said arbor when said door closure is moved to said first-named position.

3. A combined storage cabinet and rolled paper dispenser as defined by claim 2, including a latch device carried by the free end portion of said arbor and engageable with said horizontal stud upon entry thereof within the socket of said arbor for releasably holding said closure in its said first position.
